UNITED STATES PATENT OFFICE.

EZECHIEL WEINTRAUB, OF LYNN, MASSACHUSETTS, ASSIGNOR TO GENERAL ELECTRIC COMPANY, A CORPORATION OF NEW YORK.

VAPOR ELECTRIC DEVICE.

1,138,163.

Specification of Letters Patent.

Patented May 4, 1915.

Application filed March 13, 1913. Serial No. 753,947.

To all whom it may concern:

Be it known that I, EZECHIEL WEINTRAUB, a citizen of the United States, residing at Lynn, in the county of Essex, State of Massachusetts, have invented certain new and useful Improvements in Vapor Electric Devices, of which the following is a specification.

The present invention relates to vapor electric devices, particularly to what is known as the high pressure mercury arc lamp which consists essentially of an envelop of refractory material, such as fused silica, in which a vapor arc is operated at a relatively high temperature. The "high pressure lamp", also commonly known as the "quartz lamp", is quite distinct in its electrical characteristics from a low pressure lamp operated in a glass envelop. One of the best distinctions that may be drawn between these two types of lamps is the following: A low pressure, low temperature vapor lamp takes about the same voltage and consumes about the same amount of energy at starting as it does in normal operation, while a high pressure lamp starts at considerably lower voltage and at starting takes less energy than under normal operating conditions when the lamp has come to a final equilibrium. The energy consumption in a high pressure lamp, of course, is considerably greater per unit length than in a low pressure lamp, and it may be said that the high pressure lamp as now commonly constructed and proportioned operates with a consumption of more than 25 watts per inch in a tube about $\frac{1}{2}$ " in diameter. In other words, more than about 15 watts per square inch of surface. In fact the usual energy consumption is about 80 to 100 watts per inch length in a tube of this size.

To illustrate by a specific example the characteristics of a high pressure lamp, as more fully described and claimed by me in a copending application, Serial No. 753,946, it may be said that a lamp $3\frac{1}{2}$ " in length, $\frac{1}{2}$ " in diameter and proportioned as illustrated will start on a 110 volt multiple cir-

cuit at about 15 to 20 volts and take a starting current of 9 to 12 amperes, the energy consumption being 150 to 240 watts. When the lamp comes to an equilibrium, it operates at about 80 volts and 4 amperes.

It is the object of my invention to increase the efficiency and range of operation of the high pressure lamp. As contributing to this result, it includes certain structural features and also a method of operating the arc, as will be pointed out with greater particularity in the appended claims.

In the accompanying drawings, Figure 1 shows a lamp operated horizontally, Fig. 2 a vertical type of lamp, and Fig. 3 a series of curves illustrating the relations between voltage and current.

Referring to Fig. 1, the envelop 1 consists of fused quartz or silica, and is commonly exhausted to a high degree. It is provided with a cathode 2 of mercury, or other easily vaporizable material. Cooperating with this cathode at the opposite end of the tube is a solid tungsten anode 3. The anode is conveniently formed by coiling a tungsten wire in such a manner that a flat spiral is formed, the outer turn of the spiral being continued as the leading-in wire 4 so that a unitary structure results. The leading-in wire 4 and also the cathode leading-in wire 5 are sealed by fusion into sodium-magnesium boro-silicate glass, or other equivalent low expansion glass, which is integrally joined to the silica wall by gradually merging therewith in composition. In other words, the basic constituents of the glassy material progressively decrease until they blend into pure quartz. The space between the anode and the end of the tube is contracted as much as possible to avoid idle space where mercury may be condensed.

To my knowledge a high pressure quartz lamp has never been successfully operated on series circuits, that is, circuits on which the current is maintained constant and the voltage varies with the line conditions.

The operating characteristics of both the former type of high pressure lamp and my improved lamp may be more fully under-

stood by reference to Fig. 3. A high pressure lamp provided with a mercury anode, and an anode condensing chamber, if placed on a series, or constant current circuit, or if the current in the lamp is maintained constant in any other way, as by varying the steadyng resistance, has a volt-ampere characteristic as illustrated by curve A. In this curve the values of current and voltage are plotted respectively as abscissa and ordinate in a lamp of given length of tube. It will be noted that at a certain critical current value the curve rises almost perpendicularly. If it were attempted to operate such a lamp on a series circuit at a current value equal to the critical value, the voltage would rise continuously until the lamp is destroyed. When the device is provided with a solid anode the volt-ampere curve retains its general shape, but while it also becomes very steep at a certain current value, as shown by curve B, it is flatter and continues its gradual rise to a higher limit of current.

If either type of lamp were to be operated on a series, or constant current circuit, it would be necessary to limit the current value below this critical point. In the case of a lamp with a mercury anode, the efficiency is poor at the current values thus imposed by the volt-ampere characteristic. For this reason, such a lamp has never been available for this class of service. The lamp with a solid anode may be operated with high efficiency on series circuits. When a small condensing space, such as chamber 6, Fig. 1, or other cooling means is provided near the cathode, adjusted to the size of the tube and to the energy consumption, the critical point may be still farther extended, as shown by curve C. Still greater current values are thus available for operation. As the efficiency of the high pressure lamp increases at a greater rate than the energy consumed this fact is obviously of great advantage.

When a lamp constructed in accordance with the above description is operated at a current value somewhat below the point at which the volt-ampere characteristic becomes very steep, the very high efficiency of 0.35 watt per mean spherical candle power in a unit of 600 to 700 watts is obtained.

On multiple circuits the horizontal type of lamp as described in my application, Serial No. 733,946, and having a solid anode near which condensation of mercury is suppressed when operated on, say, 110 volt circuit will come into equilibrium at a certain current in the neighborhood of 4 amperes and this independently of the resistance in series, — in other words, independently of the starting current. This fact is due to the volt-ampere characteristic of the tube. I find that if the quartz tube is to be operated at a higher current value this can be done by

providing the tube with some condensing space near the cathode.

In a vertical type of lamp, in which the whole arc-containing tube is vertical, my investigations have shown that with the same dimensions the voltage is considerably higher and the current lower. In other words, the volt-ampere curve is much steeper than in the horizontal type of lamp of the same dimensions. In this case on 110-volt circuit it is impossible to run the lamp at all unless the tube is made undesirably short, while in the horizontal type no such difficulty is encountered. In this case in the vertical tube it is essential to have one or more properly proportioned condensing chambers near the cathode in order to run the tube at all under efficient conditions.

The chambers 7, 8 in Fig. 2 are preferably so located that the lamp may be started by tilting in the usual manner to establish an arc by contact of the anode and a mercury stream flowing from the cathode without permitting mercury to run into the condensing chambers. This lamp also has a mercury cathode 2, and a refractory anode 3, and is provided near the cathode with a helix 9 of tungsten to steady the arc, as described and claimed in a copending application, Serial No. 733,945, filed concurrently herewith.

On multiple circuits if the horizontal lamp is to be operated at high current value, it may be likewise provided to advantage with some condensing means at the cathode. It enables the lamp to be operated at higher current values at a given voltage. The construction in this case is like that already described in connection with the series lamp, Fig. 1.

What I claim as new and desire to secure by Letters Patent of the United States, is:—

1. The method of operating a vapor arc between a mercury cathode and a tungsten anode in an exhausted envelop which consists in impressing upon said electrodes a voltage proportioned to secure an intense contracted arc with an energy consumption in excess of 15 watts per square inch of envelop, dissipating enough heat near the cathode to raise the critical point current value at which the voltage increases abruptly, and maintaining the operating current a little below this critical point.

2. The method of operating a high pressure arc in an inclosed space between a vapor-emitting cathode and a solid refractory anode, which consists in dissipating heat near the cathode to raise the critical value of current at which the voltage increases abruptly and maintaining the operating current a little below this critical value.

3. The method of operating a high pressure mercury vapor arc between a mercury cathode and a solid anode with a variable

voltage, constant current energy supply
velop, dissipating enough heat near the
cathode to raise the critical value of current
at which the voltage consumed in the arc in-
creases abruptly without increase of current,
and maintaining the operating current
slightly below this critical value.

In witness whereof, I have hereunto set
my hand this 11th day of March, 1918.

EZECHIEL WEINTRAUB.

Witnesses:

FRANK G. HATIE.

It is hereby certified that in Letters Patent No. 1,138,163, granted May 4, 1915, upon the application of Ezechiel Weintraub, of Lynn, Massachusetts, for an improvement in "Vapor Electric Devices," errors appear in the printed specification requiring correction as follows: Page 2, line 41, for the word "valves" read *valves*; same page, line 116, for the word "valve" read *value*; page 3, line 2, strike out the syllables and words "velop, dissipating enough" and insert the words *which consists in dissipating*; and that the said Letters Patent should be read with these corrections therein that the same may conform to the record of the case in the Patent Office.

Signed and sealed this 1st day of June, A. D., 1915.

[SEAL.]

J. T. NEWTON,

Acting Commissioner of Patents.
